UNITED STATES PATENT OFFICE.

JAMES E. KENNEDY, OF WASHINGTON, DISTRICT OF COLUMBIA.

BURNER FOR GAS-STOVES.

1,070,812.

Specification of Letters Patent. Patented Aug. 19, 1913.

Application filed January 17, 1912, Serial No. 671,631.

To all whom it may concern:

Be it known that I, JAMES E. KENNEDY, a citizen of the United States, residing at Washington, in the District of Columbia, have invented new and useful Improvements in Burners for Gas-Stoves, of which the following is a specification.

The invention relates to stoves and has for an object to provide a burner therefor, for controlling the fuel supply.

The invention embodies more particularly a device whereby when a vessel is placed on the stove, fuel will be supplied to the burner and when a vessel is removed from the stove the fuel will be cut off from the burner.

For the purpose described, use is made of a pilot light mechanism, the pilot light of which is arranged in the vicinity of the burner, the mechanism being connected with the supply pipe and operable when the vessel is placed over the burner to open the supply pipe and permit a flow of the fuel to the burner, said fuel being there ignited by the pilot light, the said pilot light mechanism being operable in the reverse direction, when the vessel is removed from the stove, to cut off the supply of fuel to the burner.

In the further disclosure of the invention, reference is to be had to the accompanying drawings constituting a part of this specification, in which similar characters of reference denote corresponding parts in all the views, and in which—

Figure 1 is a plan view of a four burner stove equipped with my device. Fig. 2 is a vertical sectional view taken on the line 2—2 in Fig. 1, the pilot light mechanism being shown in closed position to cut off the supply of fuel to the burner. Fig. 3 is a similar sectional view showing the pilot light mechanism in open position to permit a supply of fuel to the burner, vessels mounted upon the stove being shown in dotted lines. Fig. 4 is an enlarged vertical longitudinal sectional view through the valve mechanism showing the valve in closed position. Fig. 5 is a similar enlarged vertical longitudinal sectional view showing the valve in open position to supply fuel to the burner. Fig. 6 is an enlarged horizontal sectional view of the valve mechanism showing the arrangement of the needle valve. Fig. 7 is a vertical sectional view taken on the line 7—7 in Fig. 6. Fig. 8 is an enlarged

vertical sectional view of the pilot light burner.

Referring more particularly to the views, use is made of a stove 10 embodying an upper plate 11 provided with apertures in which are mounted grids 12, burners 13 being mounted beneath the grids 12 and connected by burner pipes 14 and fuel controlling mechanisms 15 with a main supply pipe 16, a single independent fuel controlling mechanism 15 being provided for each burner 13, said burners 13 and said fuel controlling mechanisms 15 being similar in arrangement, construction and operation.

An actuating member 17 is mounted upon the stove 10 and comprises a bar 18 pivotally mounted on the under side of the plate 11 and engaged by a spring 19, secured to the under side of the plate 11 to normally retain an end of the said bar in uppermost position, the mentioned end of the said bar terminating in a foraminous cap 20, said cap having integrally formed therewith a bar 21, provided at one end with a slot 21^a in which is mounted to slide a pin 21^b of a bell crank lever 22 mounted to swing on the under side of the plate 11 and terminating in a depending rod 23. The mentioned spring 19, engaging the bar 18 tends to normally retain the bars 18, 21 and bell crank lever 22 in uppermost position, thus also retaining the cap 20 in uppermost position, said cap being conically shaped with the tip thereof extending slightly above the horizontal plane of the grid 12, the said cap being provided with a depending inclined peripheral flange 24 which will aid in the proper spreading of the flame which issues from the burner 13, when the cap is in lower position, it being understood that a portion of the heat from the flame will pass through the foraminous portion of the cap. It will be noted that by making the cap 20 of a conical shape with the tip extending slightly above the horizontal plane of the grid 12, a vessel can be slid onto the grid to pass over and engage the cap 20 and depress the same, thus obviating the necessity of lifting a heavy vessel to place the same over the burner 13 as will be readily understood.

The burner end of the burner pipe 14 terminates in the burner 13 as mentioned and the rear end of the burner pipe is provided with the usual air controlling valve 25 and gas cock 26, the rear end of the said burner pipe terminating in the main supply pipe 16.

Interposed in the burner pipe 14, between the supply pipe 16 and the gas cock 26, is a valve 27 comprising a rotatable valve body 28 provided with a grooved portion 29 which when the valve 27 is in open position will permit the gas in the supply pipe 16 to pass into the passage 30 of the burner pipe, said gas being adapted to flow to the burner when the gas cock 26 is in open position and prevent it from flowing to the burner when the gas cock is in closed position, the initial passage 31 of the burner pipe being at all times open and not affected by the operation of the valve body 28 as shown in Figs. 4 and 5. The valve body 28 is provided with a passage 32 and threadedly mounted upon the valve body 28, to control the supply of gas through the passage 32 is a needle valve 33 arranged to operate through a stuffing box 34 and terminating at the outer end in a suitable knurled handle 35. Threadedly connected to the valve body 28 is a pipe section 36, through which the gas in the passage 32 is adapted to flow when the needle valve 33 is in open position, the lower end of the said pipe section having threadedly connected thereto a tubular socket 37, slidably encircled by a sleeve 38 connected to a pilot tube member 39, forming a part of the fuel controlling mechanism 15, the gas in the passage of the pipe section 36 being adapted to pass into the passage of the socket 37 and thence into the tube member 39, the forward end of the tube member 39 being bent to extend upwardly beneath the cap 20 and having connected thereto a pilot light burner 40.

Mounted to encircle the pilot tube member 39 is a collar 41 pivotally connected to the lower end of the depending rod 23 by a transversely extending pin 42. It will now be readily seen that when the valve 27 is in closed position relatively to the passage 30 of the burner pipe 14, and the cap 20 is in its uppermost position, when a vessel is placed upon the grid 12 to depress the cap 20, the downward movement of the cap will operate the rod 23 thus imparting a swinging movement to the tube member 39 and rotating the valve body 28 to move the same into open position relatively to the passage 30 as shown in Fig. 5 and if the gas cock 26 is in open position at this time the gas from the supply pipe 16 will pass into the passage 30 and thence to the burner 13, it being also apparent that the flow of gas from the supply pipe 16 to the tube member 39 is not affected by the rotatable movement of the valve member 28 nor by the operation of the gas cock 26, the mentioned supply of gas to the tube member being controllable by the needle valve 33. Thus when the vessel is removed from the grid 12 the action of the spring 19 will move the cap 20 upwardly, thus operating the depending rod 23 and swinging the tube member 39, which in turn

will rotate the valve body 28 to move the same into closed position as shown in Fig. 4 to cut off the supply of gas to the passage 30 of the burner pipe 14.

The pilot light burner 40 comprises a casing 43 in which is mounted a body 44, composed of an incombustible material and provided with a longitudinally extending passage 45, the upper end of the said body extending beyond the upper end of the casing 43 and terminating in a tip 46 provided with a series of apertures connected with the passage 45. Threadedly mounted on the forward end of the pilot tube member 39 is a sleeve 47 provided with a seat 48 terminating in a passage 49, connecting with the passage 45 of the body 44, a filter member 50, such as absorbent cotton or the like, being mounted on the seat 48 and extending into the passage 49, the mentioned filter member being provided to restrict the size of the flame at the tip 46 and also to purify the gas before the same reaches the tip 46, by absorbing from the gas any moisture or foreign matter that may be contained therein.

In the operation of my device, assuming that the cap 20 is in its uppermost position, that the gas cock is in open position and that the gas passing through the tube member 39 from the supply pipe 16, is ignited at the tip 46 of the burner 40, when it is desired to heat the contents of a vessel, the vessel is slid onto the grid 12 to depress the cap 20 against the action of the spring 19, thus through the medium of the bar 21, imparting a swinging movement to the bell crank lever 22 which in turn will operate the tube member 39 to impart rotation to the valve body 28 and swing the same into open position, thus permitting the gas in the supply pipe 16 to pass into the passage 30 and thence to the burner 13, where the gas will be ignited by the pilot light of the burner 40. As mentioned heretofore when the cap 20 is in lowered position the cap will be arranged immediately above the burner and the particular construction of the cap as described will aid in properly spreading the flame at the burner while at the same time the cap will not prevent the passage of the heat produced by the flame at the burner, to the bottom of the vessel, inasmuch as the cap is provided with a foraminous portion and is arranged centrally to the burner, over the usual opening provided through the center of the burner. By operating the needle valve 33, the supply of gas to the pilot light burner 40 can be conveniently regulated and by moving the needle valve 33 into closed position the pilot light will be extinguished. The gas cock 26 is provided more particularly as an emergency or safety gas cock and by moving the gas cock 26, irrespective of the valve 27, the supply of gas to the burner 13 will be

cut off without disturbing the flow of gas from the supply pipe to the pilot light burner 40.

If it is desired to entirely cut off the supply of gas to the stove, the needle valve 33 can be moved into closed position, thus cutting off the supply of gas to the pilot light burner and if the cap 20 is in uppermost position, the valve body 28 will cut off the supply of gas to the burner. However, to more efficiently prevent any gas from flowing to the burner, the gas cock 26 can be moved into closed position and the gas will be entirely cut off from the burner and pilot light burner.

As mentioned heretofore, the burners disclosed in Fig. 1 and the fuel controlling mechanism therefor, are similar in arrangement and construction to the particular burner and valve mechanism described in detail heretofore and although for the purpose of describing the arrangement and operation of the device I have described only one burner and one fuel controlling mechanism therefor, it will be understood that any number of burners and fuel controlling mechanisms may be employed in connection with any known make of stove to accomplish the desired result.

I claim:—

1. In a gas stove, the combination with a burner, of a pilot light situated above the burner, a cock for governing the flow of gas to the burner, a gas supply pipe for the pilot light, the said pipe being adapted to operate the said cock, a yieldingly supported spreader-cap situated above the pilot light

in a position to be operated by a cooking vessel, and means for transmitting motion from the spreader-cap to the said gas supply pipe. 40

2. In a gas stove, the combination with a burner, of a pilot light situated above the burner, a cock for governing the flow of gas to the burner, a gas supply pipe for the pilot light, the said pipe being adapted to operate the said cock, a yieldingly supported spreader-cap situated above the pilot light in a position to be operated by a cooking vessel, means for transmitting motion from the spreader-cap to the said gas supply pipe, 45 and a valve carried by the gas supply pipe for controlling the supply of gas from the said cock to the said pilot light. 50

3. In a gas stove, the combination with a burner, of a pilot light normally situated above the burner, a cock for governing the flow of gas to the burner, a manually operable valve for governing the flow of gas to the burner independently of the said cock, a gas supply pipe for the pilot tube and operable to actuate the said cock, a spreader-cap situated above the pilot light in a position to be operated by a cooking vessel, and means for transmitting motion from the spreader-cap to the said gas supply pipe to actuate the same and operate the said cock. 55

In testimony whereof I affix my signature in presence of two witnesses.

JAMES E. KENNEDY.
